WOOD PULP MAKING

Peter A. Paulson, Appleton, Wis.

Application May 21, 1934, Serial No. 726,646

10 Claims. (Cl. 92—11)

This invention relates to an improved method of and apparatus for producing wood pulp for paper making, and especially to an improved sulphite process of producing wood pulp for paper making and to apparatus for carrying on the process.

The main objects of the invention are to provide a commercially practicable continuous process for producing wood pulp; to provide such a process which may be practiced with apparatus which may be easily produced or obtained and set up; to provide a process which will be efficient and economical in operation and which may be carried on in a more or less automatic manner; to provide simple but efficient apparatus for carrying on the process; and in general, it is the object of this invention to provide an improvement in the art of wood pulp making.

Other objects and advantages of the invention will be understood by reference to the following specification and accompanying drawing in which there is illustrated one selected form of apparatus for commercially producing the invention.

Referring now to the drawing, there is illustrated a receptacle or digester designated 5, which is preferably in the form of a vertically disposed elongated tank made of chrome nickel alloy steel or of other suitable material which will satisfactorily resist the corrosive effect of the acids introduced and formed in the receptacle during the production of wood pulp.

The upper end of the digester is of conical shape and is connected to a conveyor 6 of any suitable type which feeds chips to the digester from a supply hopper designated 7. The conveyor 6 may be a screw conveyor or any other suitable type which will serve to convey chips from the supply hopper to the digester.

A pipe connection 8 communicating with the interior of the digester is provided for introducing into the digester liquid containing the base, for example lime and magnesia or the equivalent which is used in the process.

The bottom of the digester is also of conical form and a series of ports designated 9 are provided in circumferential spaced relation around the digester. These ports serve to permit the introduction of the desired hot gases and steam for effecting the cooking. The ports 9 being spaced around the digester serve to effect a substantially uniform distribution of the gas and steam in the receptacle. Hot gas and steam are supplied through a manifold 10 which communicates with the ports 9 and pipe line 11 which communicates

with a separating tank 12 wherein the hot gas and steam are produced.

The chips, base-liquid, gas and steam are supplied continuously in proper proportions and pulp is accordingly produced in a continuous manner. The finished pulp is discharged from the lower end of the receptacle or digester and passed through a pipe line 13 to a level control tank 14 which is provided with a dam indicated at 15. Material flowing over the dam will pass out of the level maintaining device 14 through a pipe connection 16 into a filter or strainer 17. The filter or strainer may be of more or less conventional screen drum construction. In the said strainer or filter, the liquid is extracted from the pulp product, the liquid passing through the screen drums and emerging from the interior of the drums into a pipe line 18. The partially thickened pulp which leaves the strainer 17 through the pipe connection 19 next enters a suitable press 20 which presses more of the liquid out of the pulp. The liquor pressed out of the pulp is disposed of through a pipe 21 which carries the waste liquor to any desired disposal system and the pressed pulp emerges from the mouth 22 of the press and is conveyed to a washer in any suitable manner.

It will be seen that by reason of the dam 15 in the level controlling box 14, a predetermined level will be maintained in the digester over the top of the mixture of chips, liquid and acid.

The liquid removed from the pulp in the filter 17 is conducted by the pipe line 18 to a pump 23 which feeds the liquid under pressure to a manifold 24 surrounding the digester near its discharge end, the manifold supplying the hot liquid to the interior of the digester through a series of ports 25 which are spaced circumferentially around the digester. The introduction of the hot liquid through the ports 25 serves to thin down the pulp so as to facilitate its passage through the pipe line 13 to the level control box 14 and strainer 17. A portion of the hot liquid fed by the pump 23 is also conveyed by a pipe 26 to a nozzle 27 which enters the pipe line 13 in a position to assist the movement of the thinned pulp through the pipe line 13.

In the sulphite process of producing wood pulp, an excess of heat and sulphur dioxide gases is normally required to effect proper cooking. Excess gases rising from the mixture in the digester are permitted to escape therefrom through a vent pipe 28 which communicates with the upper end of the digester at a point above the level of the mixture. It will be apparent that no pres-

sure is produced in the digester other than that incident to the weight of the column of chips and liquid. This is possible because a constant flow of a mixture of sulphur dioxide and steam is supplied to the digester through the ports 9. Hence, the digester need not be of the usual thick construction. This thinner construction will allow the use of comparatively high grade acid-resisting metal, such as previously mentioned 10 without prohibitive expense.

Gas such as sulphur dioxide is supplied through a pipe line 29 from a suitable source of supply to a blower 29' which may be driven by an electric motor as indicated, or otherwise. The gas is 15 conveyed from the blower 29' through a pipe line 30 to an acid absorber 31 which may be of any suitable type, for example, the type commonly used in the "milk of lime system", wherein the gas is absorbed in cold water. Cold water is introduced into the upper end of the acid absorber by means of a pipe connection 32. The acid-bearing water is drawn out of the absorber by means of a suitable pump designated 33 and discharged into a pipe 34 which communicates with 20 two heat exchangers, one designated 35 and the other designated 36. A portion of the acid liquid is thus passed through the heat exchanger 35 and another portion through the heat exchanger 36.

Hot water drained from the separating tank 30 12 passes through a pipe 37 into the heat exchanger 35 to pre-heat the cold acid liquid which is supplied to this heat exchanger. The pre-heated acid liquid is conducted through a pipe 38 from the heat exchanger 35 to another heat 35 exchanger 39. Live steam enters the heat exchanger 39 through the steam inlet pipe 40 and is exhausted from the heat exchanger through the outlet pipe 41 which carries the steam condensate back to the boiler for re-heating. In the 40 heat exchanger 39, the pre-heated acid liquid from the heat exchanger 35 is raised to the desired high temperature and the hot acid liquid is conveyed by a pipe 42 from the heat exchanger 39 to the separating tank. The acid liquid which 45 enters the heat exchanger 36 receives a pre-heating from the hot gases from the vent 28, through a pipe line 43 and the pre-heated acid liquid is conveyed from the heat exchanger 36 through a pipe line 44 to the heat exchanger 39. It will 50 be seen that the pipe lines 38 and 44 are brought together and the entire supply of acid liquid is introduced to the heat exchanger 39.

In the separating tank 12, the hot acid liquid separates into hot acid gas and steam and hot 55 water. The gas and steam in its heated condition flows through the pipe line 11 into the digester as previously explained. The hot water which collects in the bottom of the tank 12 is drawn off through the pipe 37 and sent through 60 the heat exchanger 35. Inasmuch as the hot water may retain some of the acid gas in solution, the solution is desirably further cooled by being sent through a heat exchanger or cooler 45 with which the heat exchanger 35 communicates by means of a pipe connection 46. The cooled water is conveyed from the cooler 45 through a pipe line 47 which connects with the cold water pipe line 32 which enters the acid absorber. For effecting cooling in the cooler 45, 65 cold water is used, such cold water entering through the pipe line 48 and being discharged through the pipe 49.

The hot relief gases used for pre-heating the acid liquid in the heat exchanger 36, are conducted from the heat exchanger 36 to a cooling 70

coil 50 in which such relief gases are cooled and from which the cooled gases are conducted by a pipe line 51 to the pipe line 28 which supplies cooled acid gas to the blower 29'. A by-pass pipe line 52 may be provided for eliminating the pre-heating heat exchanger 36 and cooler 50 in the event that it is desired to return the relief gases from the vent 28 directly to the gas supply line 29. 5

Obviously, other arrangements may be made 10 for pre-heating and heating the acid liquid and for cooling the relief gases and the hot water drawn from the separating tank 12. However, the above described arrangement is quite economical and efficient in that it utilizes as far as 15 practicably possible all of the heat developed by the process, while also saving for re-use all of the relief gases and unused acid liquid.

Valves may, of course, be provided in the various pipe lines at desirable points for controlling 20 the flow of fluids therethrough. In the foregoing description, the valves have not been specifically mentioned, but it will be observed that such valves are illustrated in convenient locations and the effects of closing or opening the 25 valves will, of course, be apparent.

Changes in the described apparatus may be made and the method otherwise carried on without departing from the spirit of the invention, the scope of which should be determined by 30 reference to the following claims which should be construed as broadly as possible consistent with the state of the art.

I claim:

1. The process of making wood pulp which consists in supplying to the inlet end of an elongated receptacle, a mixture of wood chips and a base-containing liquid, conducting said mixture through said receptacle, introducing acid gas into said receptacle at a point spaced from the 40 chip inlet, permitting the escape of gases to prevent the development of excessive pressure within the receptacle, discharging the treated material from the other end of the receptacle, propelling cold acid gases to an acid absorber, withdrawing cold acid liquid from said absorber, heating said acid liquid by passing the same through a heat exchanger, delivering the heated acid to a separator for separating acid gas from said heated acid liquid to provide a supply of 50 said acid gas for introduction into said receptacle, passing hot liquid from said separator through said heat exchanger for heating some of said acid, and introducing the hot liquid after passing through said heat exchanger to said acid 55 absorber.

2. The process of making wood pulp which consists in supplying to the inlet end of an elongated receptacle, a mixture of wood chips and a base-containing liquid, conducting said mixture 60 through said receptacle, introducing acid gas into said receptacle at a point spaced from the chip inlet, permitting the escape of gases to prevent the development of excessive pressure within the receptacle, discharging the treated material from 65 the other end of the receptacle, propelling cold acid gases to an acid absorber, withdrawing cold acid liquid from said absorber, heating said acid liquid by passing the same through a heat exchanger, delivering the heated acid to a separator 70 for separating acid gas from said heated acid liquid to provide a supply of said acid gas for introduction into said receptacle, passing hot liquid from said separator through said heat exchanger for heating some of said acid, introduc- 75

- ing the hot liquid after passing through said heat exchanger to said acid absorber, and introducing the escaped gases from said receptacle to said absorber with said cold acid gas.
5. The process of making wood pulp which consists in supplying to the inlet end of an elongated receptacle, a mixture of wood chips and a base-containing liquid, conducting said mixture through said receptacle, introducing acid gas into said receptacle at a point spaced from the chip inlet, permitting the escape of gases to prevent the development of excessive pressure within the receptacle, discharging the treated material from the other end of the receptacle, propelling cold acid gases to an acid absorber, withdrawing cold acid liquid from said absorber, heating said acid liquid by passing the same through a heat exchanger, delivering the heated acid to a separator for separating acid gas from said heated acid liquid to provide a supply of said acid gas for introduction into said receptacle, passing hot liquid from said separator through said heat exchanger for heating some of said acid, introducing the hot liquid after passing through said heat exchanger to said acid absorber, passing said relief gas through a heat exchanger for heating some of said acid liquid and introducing said relief gases after passing through said exchanger to said absorber with said cold gas.
5. The process of making wood pulp which consists in supplying to the inlet end of an elongated receptacle, a mixture of wood chips and a base-containing liquid, conducting said mixture through said receptacle, introducing acid gas into said receptacle at a point spaced from the chip inlet, permitting the escape of gases to prevent the development of excessive pressure within the receptacle, discharging the treated material from the other end of the receptacle, propelling cold acid gases to an acid absorber, withdrawing cold acid liquid from said absorber, heating said acid liquid by passing the same through a heat exchanger, delivering the heated acid to a separator for separating acid gas from said heated acid liquid to provide a supply of said acid gas for introduction into said receptacle, passing hot liquid from said separator through said heat exchanger for heating some of said acid, introducing the hot liquid after passing through said heat exchanger to said acid absorber, passing said relief gas through a heat exchanger for heating some of said acid liquid and introducing said relief gases after passing through said exchanger to said absorber with said cold gas.
6. The process of making wood pulp which comprises the steps of conducting relief gas from a digester and fresh acid gas to an acid absorber to produce acid liquid, heating said liquid sufficiently to cause acid gas to separate from the liquid when the liquid is passed into a separator, and injecting the separated gas in the digester.
7. The process of making wood pulp which comprises the steps of conducting relief gas from a digester and fresh acid gas to an acid absorber to produce acid liquid, preheating some of said acid liquid in a heat exchanger by heat from hot relief gas from the digester, additionally heating said liquid sufficiently to cause acid gas to separate from the liquid when the liquid is passed into a separator, and injecting the separated gas in the digester.
8. The process of making wood pulp which comprises the steps of conducting relief gas from a digester and fresh acid gas to an acid absorber to produce acid liquid, preheating some of said acid liquid in a heat exchanger by heat from liquor from an acid separator, additionally heating said liquid sufficiently to cause acid gas to separate from the liquid when the liquid is passed into a separator, and injecting the separated gas in the digester.
9. The process of making wood pulp which comprises the steps of conducting relief gas from a digester and fresh acid gas to an absorber to produce acid liquid, preheating some of said acid liquid in a heat exchanger by heat from hot relief gas from the digester, preheating some of said acid liquid in a heat exchanger by heat from hot liquor from an acid separator, additionally heating said liquid sufficiently to cause acid gas to separate from the liquid when the latter is passed into said separator, and injecting the separated gas in the digester.
10. The process of making wood pulp which comprises the steps of conducting relief gas from a digester and fresh acid gas to an acid absorber to produce acid liquid, heating said liquid sufficiently to cause acid gas and steam to separate from the liquid when the liquid is passed into a separator, and injecting the separated gas and steam in the digester.

PETER A. PAULSON.
